RAILWAY PASSENGER CAR

Albert G. Dean, Narberth, Pa., assignor to The Budd Company, Philadelphia, Pa., a corporation of Pennsylvania

Application April 16, 1956, Serial No. 41,092

Term of patent 14 years

(Cl. D66—1)

Fig. 1 is a side elevation of one side of a railway passenger car embodying my new design;

Fig. 2 is a side elevation of the side of the car opposite to the side shown in Fig. 1;

Fig. 3 is a top plan view of a part of the dome end of the car; and

Fig. 4 is an end view of the car, the opposite end being substantially the same.

The essential features of my design reside in the portions shown in full lines in the drawings.

I claim:

The ornamental design for a railway passenger car, substantially as shown and described.
